DESIGN FOR A CONDUIT OR SIMILAR ARTICLE

Joseph F. O'Brien, Jersey City, N. J.

Application April 19, 1941, Serial No. 100,521

Term of patent 14 years

To all whom it may concern:

Be it known that I, Joseph F. O'Brien, a citizen of the United States of America, residing in Jersey City, county of Hudson, and State of New Jersey, have invented a new, original, and ornamental Design for Conduit or Similar Article, of which the following is a specification, reference being had to the accompanying drawing, forming part thereof.

In the drawing:

Fig. 1 is a front elevation of a conduit or similar article showing my new design.

Fig. 2 is a diagrammatic outline of the end of the conduit or similar article shown in Fig. 1.

I claim:

The ornamental design for a conduit or similar article, substantially as shown.

JOSEPH F. O'BRIEN.
